W. BAUER.

Patented Jan. 3, 1899.

CLOVER OR FLAX ATTACHMENT FOR SELF BINDERS.

(Application filed Feb. 2, 1898.)

(No Model.)

UNITED STATES PATENT OFFICE.

WILLIAM BAUER, OF RUGGLES, OHIO.

CLOVER OR FLAX ATTACHMENT FOR SELF-BINDERS.

SPECIFICATION forming part of Letters Patent No. 617,073, dated January 3, 1899.

Application filed February 2, 1898. Serial No. 668,898. (No model.)

To all whom it may concern:

Be it known that I, WILLIAM BAUER, a citizen of the United States, residing at Ruggles, in the county of Ashland and State of Ohio, 5 have invented a Clover or Flax Attachment for Self-Binders, of which the following is a specification.

My invention is a clover and flax attachment to a self-binder, in which attachment 10 are embraced the following advantages: first, that it will work automatically without the attention of the driver; second, that it can be quickly adjusted to drop off small or large gavels; third, it is light and durable, and, 15 fourth, it can be easily and quickly put on or taken off. I attain these objects by the mechanism illustrated in the accompanying drawings, in which—

Figure 1 is an entire view of the machine, 20 looking from the binder end of the machine. Fig. 2 shows the bottom of the machine and how it is attached to the binder. Fig. 3 shows a rear end view and the gearing that runs the machine. Fig. 4 is an enlarged view of the 25 gearing in Fig. 3, showing how it is attached to the binder and the friction-clutch. Fig. 5 is a cross-section of Fig. 4, showing how it is attached to the binder. Fig. 6 shows the opposite side of Fig. 3 and shows the trip on 30 rake-wheel C and the trip-lock and spring.

Similar letters refer to similar parts throughout the several views. The small letters of the alphabet are used for the framework and the large letters of the alphabet are used for 35 the gearing.

In Fig. 1, A is the rake-beam. B B are the 40 rake-teeth, tipped with iron, so that they will go through the clover and flax easily. C is a wheel on rake-beam A. (Shown more fully in Figs. 3 and 6.) D is the trip on rake-wheel 45 C. a is the main table-beam. (Shown best in Fig. 2.) b is the front top cross-beam. c is the rear top cross-beam. e e is the brace-beam; f f, the braces. g is the connecting-table. j is a spring fitting in block s, so that 50 the beam A can be taken out. k k are the long table-bars. l l are the short table-bars. m is a shield to protect the gearing. n n is a front shield. o is the front bottom beam; 55 p, a beam connecting beams o b.

In Fig. 2 main table-beam a is shown, also

upper beam h and a short beam i, connecting table g by the hinges u u. E is the driving-shaft of the binder. H is the journal on main shaft E. I is the pivoted journal-box, 55 which can be drawn to one side (shown by the dotted lines in Fig. 2) when you want to detach the machine, or put in position and fastened by a journal-fastener J and fastened by a hook K. Journal-fastener J can also be 60 drawn to one side, as shown by the dotted lines. t is a bottom cross-beam. The machine is quickly and easily put on or taken off.

Fig. 3 shows the gearing of the machine run by the shaft E of the binder. C is a cog-wheel on the rake-beam A. It is run by a small pinion L on shaft M, connecting with the drive-shaft E. Wheel C has two places on opposite sides without cogs, (shown by F,) so that the pinion L can run all the time. 70 The cog-wheel C stands still until the weight of the grain disengages it from trip-lock W and turns it far enough to be caught by the pinion L. It will then make a half-revolution, turning the rake-beam A, and throwing off 75 a gavel. A half-revolution is made for each gavel. M is the shaft connected with main shaft E, held by bracket Y in corner of frame. N is a bur on shaft M, so that the spring on shaft M can be made to bear heavier or lighter 80 on friction-clutch O. P is a bevel cog-wheel connected with cog-wheel R on shaft E. Fig. 4 shows how it is attached to drive shaft E, looking down on it, and also an enlarged view of cog R, fastened by a screw R', 85 and cog-wheel P and friction-clutch O. The cog-wheel P is movable on shaft M. The friction-clutch O, having a slot in it, in which is a bolt T through the shaft M, is held against cog-wheel P by a spring. By this means the 90 gearing cannot break if the machine should clog. It will trip over when the pressure is too hard.

Fig. 5 is a cross-section of Fig. 4, showing the bolt T through shaft M and friction-clutch 95 and bolt U to hold cog-wheel P on the shaft; also, how it is fastened to the binder by the piece S by means of bolts. When the piece S is taken off, the piece Q, which fits in a groove in the hub of the cog-wheel R, can be 100 taken off, which detaches the gearing from the binder.

Fig. 6 is the opposite side of cog-wheel C, which shows the trips D D, which are adjusted by bolts and slots and the trip-lock W, which is held by a spring V, adjusted by a bolt V'. By this arrangement the machine can be adjusted to throw off gavels of any size.

The rake can be taken off readily, as shown in Figs. 1 and 3, by pressing down the spring 10 j in Fig. 1 and slipping the rake up and by moving the block Z and moving the frame w to the side, as shown in Fig. 3.

What I claim as my invention, and desire to secure by Letters Patent, is—

15 1. In a clover and flax attachment to a self-binder, trips D D, trip-lock W, spring V, and

a mutilated cog-wheel C, substantially as described.

2. In a clover and flax attachment to a self-binder, two slotted trips, a trip-lock, a spring, 20 a bolt and a mutilated cog-wheel, substantially as described.

3. In combination, rake-beam A having teeth B B, and a mutilated cog-wheel C, trips D D, shaft E, trip-lock W and spring V, all 25 substantially as described and for the purpose set forth.

WILLIAM BAUER.
